Primary Examiner — Marissa J Cash*Assistant Examiner* — Rebecca Tsehayé(74) *Attorney, Agent, or Firm* — Brandon V. Zuniga; James R. Gourley; Carstens & Cahoon, LLP(57) **CLAIM**

The ornamental design for an electronic cigarette pod, as shown and described.

DESCRIPTION

FIG. 1 is a perspective view from the front, left side and above of an electronic cigarette pod;

FIG. 2 is a front elevation view of the pod;

FIG. 3 is a rear elevation view of the pod;

FIG. 4 is a left side elevation view of the pod;

FIG. 5 is a right side elevation view of the pod;

FIG. 6 is a plan view from above of the pod; and,

FIG. 7 is a plan view from below of the pod.

In FIGS. 1, 6 and 7: (i) broken lines and portions of the electronic cigarette pod contained by the broken lines depict portions of the electronic cigarette pod that form no part of the claimed design, and (ii) the regions of the electronic cigarette pod that are shown in a lighter tonal value and depicted with a broken line along the perimeter of the regions form no part of the claimed design.

1 Claim, 7 Drawing Sheets(56)
